UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT.

STEM-WINDING AND STEM-SETTING WATCH.

Application filed November 15, 1924. Serial No. 750,085.

Fig. 1 is a view in front elevation of a stem-winding and stem-setting watch embodying my invention, with the parts of its winding-and-setting mechanism shown in their normal or winding positions.

Fig. 2 is a corresponding view, with the parts shown in their occasional or setting positions.

Fig. 3 is a sectional view on the line 10 3—3 of Fig. 1.

Fig. 4 is a sectional view on the line 4—4 of Fig. 1.

Fig. 5 is a detached, inside face view, on an enlarged scale, of the yoke-unit.

Fig. 6 is an edge view thereof.

Fig. 7 is a detached view, on the same scale, of the yoke-shifter.

Fig. 8 is an edge view thereof.

My invention relates to an improvement 20 in that class of stem-winding and stem-setting watches in which the stem is pulled out for setting, the object being to produce a simple, compact, durable and reliable winding-and-setting mechanism constructed 25 with particular reference to that rigid economy of space demanded in the production of wrist-watches.

With these ends in view, my invention 30 consists in a pull-out-for-setting, stem-winding and stem-setting watch having certain details of construction and combinations of parts as will be hereinafter described and particularly pointed out in the claim.

In carrying out my invention, as herein 35 shown, the front and rear movement-plates 10 and 11 mount a bridge 12 interposed between them and itself mounting a primary winding-and-setting wheel 13 having a square opening receiving the squared portion 14 of a longitudinally-movable and rotatable winding-and-setting stem 15 furnished at its outer end with an ordinary crown 16 and formed at its inner end with a coupling-groove 17 entered and embraced 45 by a pair of coupling-fingers 18 flanking a clearance-cut 19 in a plate-like yoke-shifter 20 mounted upon a hub 21 having pintles 22—22 journalled in the respective front and rear movement-plates 10 and 11.

The plate-like yoke-shifter 20 is formed 50 with an L-shaped yoke-shifting and yoke-locking slot 23 comprising a shifting-edge 24 and a locking-shoulder 25. The said slot 23 receives a pin 26 extending inwardly 55 through a slot 27 in the front movement-

plate 10 from the right-hand arm of a substantially T-shaped yoke 28 located adjacent to but not bearing upon the front face of the front movement-plate 10 and swinging upon a shouldered stud 29 having a large flat 60 retaining-head 30 and riveted into the said plate 10.

The shouldered stud 29 mounts an intermediate winding-and-setting wheel 31 constantly in mesh with the primary winding-and-setting wheel 13 aforesaid and also constantly in mesh with a secondary winding-and-setting wheel 32 mounted upon a stud 33 fixed in the lower end of the yoke and projecting at its inner end into a limiting- 65 slot 34 in the plate 10. The said wheels 31 and 32 are interposed between the yoke and the front face of the front movement-plate in the very narrow space between the said yoke and plate produced by shouldering the 70 stud 29 upon which the wheel 31 turns, while the wheel 32, which is carried by the yoke upon the stud 33, is oscillated back and forth with the yoke. The stud 33 projects into the limiting-slot 34 in the said 75 front movement-plate but does not extend sufficiently beyond the inner face thereof to interfere with the center wheel of the time-movement.

The left-hand arm at the upper end of 80 the yoke 28 carries a pin 35 extending inward through a clearance-slot 36 in the plate 10, into position to be engaged by a yoke-spring 37 carried by the upper left-hand 85 pillar 38 of the movement and looped over a stud 39 in the plate 10. The said spring 37 normally holds the yoke in its winding position, in which the secondary winding-and-setting wheel 32 is maintained in mesh 90 with the main winding-wheel 40, as shown 95 in Fig. 1.

When the stem 15 is pulled outward for setting the watch, the yoke-shifter 20 is swung from right to left, causing its shifting-edge 24 to press against the pin 26 and 100 rock the yoke 28 from right to left against the tension of the spring 37, whereby the wheel 32 is brought into mesh with the plate-setting wheel 41 turning on the stud 42 and constantly in mesh with the dial-wheel 43, which is constantly in mesh with the center pinion 44.

As the yoke-shifter 20 approaches the limit of its swinging movement from right to left, its locking-shoulder 25 moves over 105 110

the pin 26 and locks the yoke in its setting position, as shown in Fig. 2. After the conclusion of the setting operation, the stem 15 is pushed inward and the yoke-shifter 20 5 is swung from left to right, whereby the shoulder 25 is disengaged from the pin 26, releasing the yoke 28 to the action of the yoke-spring 37, which immediately swings the yoke back into its normal, or winding, 10 position, its wheel 32 being thus de-meshed from the wheel 41 and intermeshed with the wheel 40.

Under the construction described, the yoke and yoke-shifter may be moved so close 15 to the center of the watch-movement without collision with the center-wheel of the time-train thereof as to enable the same to be reduced to the standard diameters of wrist-watches without impairment of reliability of operation or inconvenience of 20 access for attention and repair.

I claim:

In a stem-winding and stem-setting watch 25 of the type in which the stem is pulled out for setting, the combination with the front and back movement-plates thereof, of winding-and-setting trains, a longitudinally-

movable and rotatable winding-and-setting stem, a primary winding-and-setting wheel through which the said stem passes and 30 which is turned in either direction thereby, a pivotal yoke-shifter located between said plates and directly connected with the said stem, a pivotal yoke located adjacent to but not bearing upon the front face of the 35 front movement-plate and connected with the said yoke-shifter for movement thereby, a shouldered stud upon which the said yoke pivots, an intermediate winding-and-setting wheel interposed between the said yoke and 40 the front face of the front-movement plate and turning upon the said stud, a secondary winding-and-setting wheel also interposed between the said yoke and the front face of the front movement-plate and swung, with 45 the yoke, into engagement with a member of the said setting-train when the winding-and-setting stem is pulled outward, and a pin carried by the yoke, mounting the wheel last mentioned.

In testimony whereof, I have signed this specification.

WILSON E. PORTER.
